CENTRALIZER FOR DRILL STEELS

George H. Fuehrer, Phillipsburg, N. J., assignor to
Ingersoll-Rand Company, Jersey City, N. J., a
corporation of New Jersey

Application May 25, 1938, Serial No. 209,895

4 Claims. (Cl. 255—45)

This invention relates to rock drills, and more particularly to a centralizer for a drill steel actuated by a rock drill of the reciprocatory type.

In drilling operations in which the rock drill lies in an inclined position it is difficult to maintain the cutting end of the drill steel in alignment with the rock drill during the starting of a drill hole. This is due to various causes but chiefly to the natural clearances between the chuck mechanism of the rock drill and the drill steel and the inherent resiliency of the drill steel.

Unless the overhanging portion of the drill steel is stabilized it will whip about its axis and, in many instances, start the drill hole at a point off-set from the axis of the rock drill. This, as will be readily appreciated, necessitates a readjustment of the rock drill to bring it into alignment with the drill hole, otherwise the drill steel will be placed under serious strains and excessive localized wear will occur on the chuck parts.

It is accordingly an object of the present invention to stabilize the overhanging portion of the drill steel and thereby assure the correct starting of a drill hole.

Other objects will be in part obvious and in part pointed out hereinafter.

In the drawing accompanying this specification and in which similar reference numerals refer to similar parts,

Figure 1 is a longitudinal side elevation of a rock drilling mechanism equipped with a centralizer constructed in accordance with the practice of the invention.

Figure 2 is a transverse view taken through Figure 1 on the line 2—2.

Figure 3 is a transverse view taken through Figure 2 on the line 3—3, and

Figure 4 is a plan view, partly in section.

Referring more particularly to the drawing, 20 and 21 designate the front ends of a rock drill and a shell, respectively, and 22 a drill steel, the shank of which may extend into the front end 45 of the rock drill 20 to receive the blows of a hammer piston (not shown). The opposite or free end of the drill steel 22 constitutes the cutting bit 23 for drilling holes into rock 24.

The rock drill 20 and the shell 21 are of the type that are usually provided with interlocking cutting elements (not shown) to enable the rock drill to be advanced toward the work in accordance with the progress of the drill steel thereinto.

The centralizer, constructed in accordance

with the practice of the invention and designated in its entirety by 25, is attached to the front end of the shell 21. It comprises a support 26 having a flange 27 which seats against and is clamped to the front end of the shell 21 by bolts 28. In the opposite end of the support 26 are a pair of bolts 29 serving as pivots for guide arms 30 which maintain the drill steel 22 in alignment with the rock drill 20.

The bolts 29 are inclined with respect to the longitudinal axis of the support 26 and are arranged angularly with respect to each other. They lie in different transverse planes, although in close proximity to each other, and have longitudinally extending flattened surfaces 31 which engage each other to prevent rotary movement of the bolts in the support.

The guide arms 30 are arranged on the portions of the bolts 29 extending above the support and are provided with hubs 32 having bores 33 through which the bolts 29 extend. The bores 33 are of larger diameter than the bolts to receive bushings 34 which serve as wearing members between the bolts and the hubs. Each bore 33 comprises an enlarged portion 35 and a reduced portion 36. These portions define a shoulder or seat 37 for a spring 38 acting against a shoulder 39 of the bushing 34 to press the hubs 32 against seating surfaces 40, on the support 26, encircling the bolts 29. The spring 38 also forces the bushing 34 firmly against a guard or cover 41 and presses the cover against the head 42 of the bolt 29. The guard extends beyond the periphery of the hub 32 and has a depending skirt portion 43 to prevent the entrance of dust into the bore 33 and into the bushing 34.

The bolts 29 extend with their threaded ends exteriorly of the support 26 and are provided with nuts 44 which seat against the lower surfaces of the support 26 for holding the bolts 29 in position and for adjusting the tension of the springs 38.

In order to assure the correct location of the guide arms, both in the guiding and non-guiding positions, the hubs 32 and the seating surfaces 40 are provided with portions adapted to interlockingly engage each other. Preferably these portions are in the form of ribs 45 on the ends of the hubs 32 and grooves 46 in the surfaces 40 to accommodate the ribs. Any suitable number of ribs 45 and grooves 46 may be provided to assure ample locking contact between the guide arms and the support for preventing undue vibratory movement of the guide arms.

Additional means are, however, provided to as-

sure the retention of the guide arms in the guiding position. To this end the opposed surfaces of the guide arms 30 are provided with recesses 47 for the accommodation of a latch 48 which is mounted on a pivot 49 seated in the support 26. On the free end of the latch 48 is a hook 50 to engage the forward surfaces of the guide arms and the latch 48 is held by a spring-pressed plunger 51 arranged in the support 26 beneath the latch and intermediate the pivot 49 and the hook 50.

As a preferred arrangement the latch 48 is disposed in the upper surface of the support 26 and has a cam surface 52 which lies in the path 15 of the rock drill 20 so that the rock drill, when it approaches the arms 30, will engage the cam surface 52 to depress the latch 48 for releasing the guide arms.

The arm portions of the guide arms 30 may 20 be of any suitable design. In the present instance they are provided with reinforcing ribs 53 which extend from the hubs 32 to the free ends of the guide arms wherein are formed the recesses 54 through which the drill steel 22 extends.

In the operation of the device, whenever it is desired to start a drill hole the arms 30 are rocked to the guiding positions in which the drill steel 22 lies in the recesses 54. In this position of the 30 guide arms the ribs 45 lie in the grooves 46 and the latch 48 will be in engagement with the arms 30 for holding them stationary.

The arms remain in the guiding position during the ensuing drilling operation, and when the 35 rock drill advances into contact with the cam 52 the latch will be depressed to move the hook 50 out of engagement with the guide arms. Upon further forward movement the rock drill will 40 engage the guide arms and rock them out of its path and into a position in which the ribs 45 will lie in other grooves 46 where the guide arms will be securely held by the springs 38 until again

returned to the guiding position by the operator.

I claim:

1. A centralizer for drill steels, comprising a support, a pair of guide arms, pivots on the support for the guide arms, portions on the guide arms and the support interlockingly engaging each other in the guiding and non-guiding positions of the guide arms, and springs encircling the pivots acting on the guide arms and the pivots to maintain said portions in interlocking 10 engagement.

2. A centralizer for drill steels, comprising a support, a pair of guide arms, pivots on the support for the guide arms, portions on the guide arms and the support interlockingly engaging 15 each other in the guiding and non-guiding positions of the guide arms, springs encircling the pivots acting on the guide arms and the pivots to maintain said portions in interlocking engagement, a latch on the support to engage the guide 20 arms for locking said guide arms in guiding position, and a spring to press the latch means into and hold it in engagement with the guide arms.

3. A centralizer for drill steels, comprising a support, a pair of guide arms, pivots in the support for the guide arms arranged angularly with respect to each other, latch means on the support movable into and out of engagement with the guide arms to retain the guide arms in guiding position and to release the guide arms, and 30 a spring to press the latch means into and hold it in engagement with the guide arms.

4. In a centralizer for drill steels, the combination of a guide shell and a rock drill slidably thereon, a support on the shell; a pair of guide arms, pivots on the support for the guide arms, a latch on the support to engage the guide arms for locking said guide arms in guiding position and having a portion for engagement with the rock drill whereby the latch is disengaged from the 40 guide arms when the rock drill approaches said guide arms.

GEORGE H. FUEHRER.
